(57) **CLAIM**

The ornamental design for a hand grip exercise device, as shown and described.

DESCRIPTION

FIG. 1 is a front view of a hand grip exercise device in accordance with a first embodiment;

FIG. 2 is a rear view thereof;

FIG. 3 is a top plan view thereof;

FIG. 4 is a side view thereof;

FIG. 5 is a bottom plan view thereof;

FIG. 6 is front view of a hand grip exercise device in accordance with a second embodiment;

FIG. 7 is a rear view thereof;

FIG. 8 is a top plan view thereof;

FIG. 9 is a side view thereof; and,

FIG. 10 is a bottom plan view thereof.

The broken lines depict portions of the hand grip exercise device that form no part of the claimed design.

1 Claim, 10 Drawing Sheets
